ATTORNEY

UNITED STATES PATENT OFFICE.

ROBERT SANFORD RILEY, OF WORCESTER, MASSACHUSETTS, ASSIGNOR TO SANFORD RILEY STOKER COMPANY, OF WORCESTER, MASSACHUSETTS, A CORPORATION OF MASSACHUSETTS.

PULVERIZING MACHINE.

Application filed July 21, 1924. Serial No. 727,241.

To all whom it may concern:

Be it known that I, ROBERT SANFORD RILEY, a citizen of the United States of America, residing at Worcester, in the county of Worcester and State of Massachusetts, have invented certain new and useful Improvements in a Pulverizing Machine, of which the following is a full, clear, and exact specification.

10 My invention relates to fuel pulverizing apparatus and more particularly to the construction of a pulverizer of the type shown in the patent to Blyth, No. 1,446,151, of Feb. 20, 1923.

15 A machine of this type comprises a cylindrical casing carrying a number of stationary pegs on the two sides thereof between which rotates a disc or rotor carrying pegs on each of its sides. The material to be pulverized is fed into the central portion of the casing and is broken into fine particles by impact against the pegs and the peripheral wall of the casing.

20 It is found that these pegs wear away rapidly owing to the enormous friction imposed thereon and if hard materials get into the machine some of the pegs may be broken off. Hence it is necessary to remove the old pegs frequently and to replace them with new ones. Considerable difficulty has been met heretofore in fastening the pegs to their supports and making them easily and quickly removable and renewable.

25 The pegs are ordinarily made by casting in a mold, and they are mounted in sockets or holes in the rotor or casing sides. A casting has a rough irregular surface, hence it cannot be fitted accurately into a socket but must be machined or otherwise given a

30 smooth surface to permit of such assembly. This means expense and delay. Moreover, if a peg is made of cast iron or other brittle material, and it is fastened rigidly at one end to its support, a sharp blow may break it. Such breakage is serious, in that a loose

35 peg carried around in the machine may serve to break the other pegs and so do considerable damage and cause the furnace to be shut down for extensive repairs to the pulverizer. Also, if the peg is made of a hard

material, which cannot be machined, the problem must be faced of finding a suitable way of mounting the peg on its support. Heretofore, this has been done by grinding a cylindrical end on the peg and then keying the peg in a similarly shaped hole. This procedure is objectionable because of the high cost of making and assembling the peg and because the shape of the inner end of the peg is necessarily limited to one which may be produced by grinding.

40 It is the main purpose of my invention to provide a construction which overcomes these difficulties and allows one to replace worn out pegs quickly and easily, and to employ rough surfaced pegs made of cast metal.

45 It is a further object of this invention to provide an improved construction of a pulverizing apparatus suitable for breaking up coal in which the pulverizing impact pegs may be placed loosely in position and clamped removably to their support whereby the pegs may be readily removed when required.

50 It is another object of my invention to provide a mounting for the pegs which cushions the shocks and permits the pegs to yield slightly if the strain thereon becomes too great, and thereby minimize breakage and incident delays and expense in making repairs.

55 A still further object is to provide a construction which makes it feasible to use an unmachined, durable, long-lived metal for the peg body and to fashion the supported end of the peg in any shape which is desirable for the purpose of obtaining an efficient operation of the machine.

60 With these and other objects in view as will be apparent to one skilled in the art, my invention resides in the combination of parts set forth and described in the specification and covered by the claims appended hereto.

65 Referring to the drawings which illustrate one embodiment of my invention and in which like reference numerals indicate like parts:

70 Fig. 1 is a fragmentary vertical eleva-

100

tion of a portion of the casing and rotor of the pulverizer taken on the line 1—1 of Fig. 2;

5 Fig. 2 is a fragmentary vertical section on the line 2—2 of Fig. 1;

Fig. 3 is an enlarged cross section showing the mounting of the peg;

Fig. 4 is a section at right angles to the view shown in Fig. 3;

10 Fig. 5 is a top plan view of a peg removed from its support; and

Fig. 6 is a fragmentary cross section showing a modified manner of fastening a peg body in its ferrule.

15 Referring to the drawings, I have there shown a portion of a pulverizer of the type illustrated in the Blyth patent, in which the framework 10 suitably supports a rotatable shaft 11 adapted to carry the rotor and 20 its grinding pegs. The rotor 12 is essentially a thin disc mounted to rotate between the parallel walls 14 and 15 of the casing, which is substantially cylindrical in shape and has an outer peripheral wall 16 connecting the side walls 14 and 15. A wear plate 25 or liner 17 may be mounted within the wall 16 to receive the impact of the coal particles as they are thrown against it, and this plate is ordinarily made removable so that it may 30 be replaced when worn out. The casing and the frame part may be suitably constructed in order to permit assembly of the rotor, the wear plate and the pegs, and except as hereininafter described, this construction does not 35 form a part of my invention.

40 A plurality of metal pegs 20 are mounted on the inner faces of the walls 14 and 15 and project inwardly parallel with the shaft 11, these pegs being preferably arranged in concentric circles. The rotor 12 carries similar pegs 22 and 23 on its opposite sides and these are arranged also in concentric circles, in such a position that they may rotate between the pegs disposed on the casing walls, 45 whereby any material fed into the central zone of the machine through the opening 24 is caused to pass outwardly through the zone 25 formed between the pegs on the wall 14 and pegs 22, where it is pulverized by impact with the rotating pegs, the stationary pegs and the liner 17. This material must pass around the periphery of the rotor 12 through the annular space 26 and thence inwardly 50 against the centrifugal action set up by the rotating pegs to the central zone where it passes outwardly through the opening 27 into a fan chamber, not shown, from which it is driven into the combustion zone of a furnace.

55 60 In accordance with my invention, I propose to employ pegs of a hard unmachinable metal, such as manganese steel or white iron, and fashion them in place on the rotor or the casing by means which permit yielding movement thereof under severe strain, as

well as enables them to be readily removed for replacement. The peg is preferably fixed to a yielding or resilient member, which in turn is fastened to the supporting part, whereby severe shocks are absorbed 70 and the peg body is free to move to a slight extent. One simple scheme involves fastening the peg bodies rigidly but yieldingly in a flanged ferrule of a resilient material and clamping the flange against its support by 75 a locking plate. To this end I may make the peg support of two plates, one having a socket from which the peg body projects and the other being arranged to clamp the flange between the two plates. The socket is pref- 80 erably larger than the ferrule, so that the ferrule is held only by its flange. Moreover, I prefer to make the socket and the interfitting end of the peg of an elongated shape 85 in the direction of impact and thus provide a strong mounting for the peg.

As illustrated, the rotor may be made of two plates 30 and 31 suitably bolted between a flange 32 on the sleeve 33 keyed to the shaft 11 and a clamping ring 34. Each plate 30 and 31 of the rotor is provided with a series 90 of holes 35 arranged in concentric circles which are substantially of the shape of the cross section of the pegs. In order to make it feasible to utilize roughly cast peg bodies 95 which need not be machined or ground to fit in the supporting plate, I provide ferrules, which may be accurately shaped in a die, and fix the peg bodies therein, as by casting. Each metal ferrule 36 has a shank 37 of such 100 a size that it will pass easily into the hole in the plate in which the peg is to be mounted, and if desired a slight clearance may be left, so that the peg will be supported mainly by the resilient steel flange clamped between 105 its supporting plates. This ferrule is also provided with a flange 38 arranged to be mounted in a plane substantially parallel with the surface of its supporting plate, whereby the flange may be clamped between 110 the two plates 30 and 31. The flange is shown as coextensive with the end of the peg.

115 My preferred manner of fixing the peg body in the ferrule is by casting. As shown in Figs. 3, 4 and 5, the ferrule may be provided with inwardly projecting ribs or lugs 39 and if desired an inwardly turned lip 40 on its inner edge. The peg body 41 is integrally fixed in the ferrule preferably by casting it in place, in accordance with well 120 known foundry practice. The lug 39 and lip 40 serve to lock the body and the ferrule together, but if they are made of a drawn metal, they permit the peg to be drawn gradually and yieldingly from the ferrule 125 when subjected to any large stress.

130 If the peg is to be made of a high melting metal such that pouring the molten metal directly into the ferrule might injure the latter, I may make use of the scheme illus-

trated in Fig. 6. As there shown, the peg 45 and the ferrule 46 may be separately formed and then united by a casting operation. To this end, the ferrule may be provided with internally projecting ribs or lugs 47 and the peg with a groove 48, the parts being so shaped that clearance is provided for assembling. After the peg has been put in position, a comparatively low melting metal, such as babbitt, is poured into the space between the peg and the ferrule and permitted to harden in place thus forming a connecting film or layer 49 which fastens the two parts integrally together.

15 The pegs 20 may be mounted on the casting in a similar manner. In this case the ferrules are inserted in holes in the cheek plate 50 with their flanges projecting outwardly and the flanges are clamped in place

20 by a locking plate 51 which may be fastened to the cheek plate 50 by means of set screws 52. This combination of locking plate and cheek plate is in turn mounted by suitable set screws 53 on the inner wall of the casing walls 14 and 15. The pegs on the rotor are arranged with their flanges between the two plates 30 and 31, with the grinding bodies projecting on each side through the holes in the plates; hence each plate serves both as

25 a support for one group of pegs and as a clamping plate for the other set. It is found that the flange of the peg may be made of various materials which have the property of yielding slightly under abnormal stresses

30 and of absorbing the shocks and minimizing breakage of the peg, and that a ductile, malleable or resilient material formed into a thin supporting body, such as a flange of drawn steel, is particularly suited for this purpose. Such a flange will absorb any unusual stress applied to the peg, due to its slight resiliency, and leave the peg in its initial position; but in some instances the flange draws partly out of its fastening and the peg may even move in the ferrule so that the peg will assume a new and permanent position. The hole or socket in the plate is made larger than the ferrule, so as to give room for movement of the peg and the ferrule, and yet normally prevent contact of the peg body or the adjacent supporting part of the ferrule with the side of the hole or socket in the plate. This insures a yielding mount for the peg, hence any unusual stress will not ordinarily break the peg but will be absorbed by the supporting flange or serve merely to draw the peg gradually from its initial position in the ferrule or to move the ferrule from its initial position in the socket.

35 The peg body is preferably made of a noncircular cross section and wider in one direction than in another, as shown in Figs. 3, 4 and 5, and the narrower side of the peg is so located on the rotor or the casing that

the blows and friction due to the impact action will be received thereon. This insures a longer life to the peg and gives it greater rigidity in its mounting because the flange is likewise extended in the direction 70 of travel or impact of the peg. It will also be noted that the peg is not separable from its ferrule except under abnormal stresses and that they are removable and replaceable together. Moreover, this construction makes 75 it feasible to use a peg of ungrindable shape and unmachinable material, as is often desirable, and to mount it easily and removably in a socket on its support which may be easily formed. It will be obvious that 80 various modifications may be made in the shape of the parts and in the manner of mounting and assembling them within the scope of the appended claims.

Having thus described my invention, 85 what I claim as new and desire to secure by Letters Patent is:—

1. A pulverizing machine comprising a casing, a rotor mounted therein, metallic bodies mounted on one of said parts and arranged to pulverize material by impact thereagainst, and a substantially rigid mounting to hold each of said bodies fixedly in position on its supporting part under the normal stresses of pulverizing the material, 95 but which permits a slight yielding movement of said body only under abnormal stresses.

2. A pulverizing machine comprising a casing, a rotor mounted therein, impact bodies arranged to be supported on one of said parts, a substantially rigid, but slightly resilient metal mounting for each body and means to fasten only the resilient mounting firmly to the supporting part, said mounting being constructed and arranged to hold the body unyieldingly under normal pulverizing stresses but to partially absorb abnormal stresses and minimize breakage of 110 said body.

3. A pulverizing machine comprising a casing, a rotor mounted therein, metallic impact peg bodies having yielding flanges fixed thereon and arranged to be supported on one of said parts, and means removably clamping each flange tightly on the supporting part so arranged that the peg body is supported only by its flange.

4. A pulverizing machine comprising a casing, a rotor mounted therein, one of said parts comprising two juxtaposed plates, and a set of pegs having flanged ferrules rigidly fixed thereon which are removably clamped between the plates.

5. A pulverizing machine comprising a casing, a rotor mounted therein, a set of impact pegs having yielding metal flanges integral therewith arranged to be supported on one of said parts, said supporting part having sockets therein larger than the pegs, 130

and means to clamp each peg flange firmly on the supporting part with the peg loosely positioned in a socket.

6. A pulverizing machine comprising a casing, a rotor mounted therein, one of said parts having sockets of noncircular cross section therein, metallic impact peg bodies of unmachinable material having end portions shaped to be inserted freely in said sockets, and means removably fastening said bodies on their support and within the sockets, said parts being so arranged that the pegs may pulverize material by impact.

7. A pulverizing machine comprising a casing, a rotor mounted therein, one of said parts having a plate provided with sockets, flanged ferrules supported in said sockets, a peg body rigidly mounted in and projecting from each ferrule, and a plate clamping the flanges of the ferrules against the supporting plate and locking the pegs in position.

8. A pulverizing machine comprising a casing, a rotor mounted therein, a set of pulverizing pegs having flanges rigidly attached thereto, and means to mount the pegs on one of the machine parts including a plate having a hole in which the peg fits loosely and means to clamp only the flange against said plate.

9. A pulverizing machine comprising a casing, a rotor mounted therein, opposed sets of pegs on the casing and rotor between which material is pulverized by impact, the support for one set of pegs having sockets therein, a ferrule in each socket having a flange engaging one side of said plate, a peg body united with the ferrule by casting and projecting from the socket, and means engaging said flange and holding the peg in its socket.

10. A pulverizing machine comprising a casing, a rotor mounted therein, opposed sets of attrition pegs on said parts between which material is pulverized by impact, the support for one set of pegs comprising a

plate having sockets therein, flanged ferrules fitting loosely in said sockets with the flanges contacting with the face of said plate, peg bodies fixed in said ferrules by casting, and a locking member removably fastened to said plate and clamping the flanges therebetween.

11. A pulverizing machine comprising a casing, a rotatable shaft mounted therein, two juxtaposed disk plates fastened on said shaft, each having holes therethrough, hollow drawn metal flanged ferrules having hard metal attrition bodies fixed therein by casting, and projecting therefrom, said ferrules being located in the holes in each plate with the flanges between the plates and the peg bodies projecting outwardly, and means to fasten the plates together and clamp the flanges between the plates and hold the pegs in position.

12. An attrition peg for a pulverizing machine comprising a hollow ferrule having a relatively thin and wide flange of yielding material thereon, and a hard metallic body integrally fastened in the ferrule by casting and projecting therefrom.

13. An attrition peg for a pulverizing machine, comprising a hollow drawn metal ferrule having a wide flange, and a hard metallic body integrally fixed by casting in and projecting from the ferrule, said peg and ferrule being wider in one direction than in another and the flange being substantially coextensive with the end of the peg body.

14. An attrition peg for a pulverizing machine comprising a hollow open ended ferrule of drawn metal having an outwardly extending flange and an inwardly projecting lug, and a peg body cast in and projecting from one end of said ferrule and arranged to be held in place by said lug under normal stresses.

Signed at Worcester, Massachusetts, this 19th day of June, 1924.

ROBERT SANFORD RILEY.
